WO 2011012739 A1* 2/2011 ..... B60R 13/0206

Primary Examiner — Richard E Chilcot

(57) **CLAIM**

The ornamental design for an in-vehicle accessory attachment clip, as shown and described.

DESCRIPTION

FIG. 1 is a front view of an in-vehicle accessory attachment clip, where the in-vehicle accessory attachment clip is shown in a first position of use, according to the invention. FIG. 2 is a rear view thereof.

FIG. 3 is left side view thereof.

FIG. 4 is a right side view thereof.

FIG. 5 is a top view thereof.

FIG. 6 is a bottom view thereof.

FIG. 7 is a front view thereof, where the in-vehicle accessory attachment clip is shown in a second position of use. FIG. 8 is rear view thereof.

FIG. 9 is a side view thereof.

FIG. 10 is a top view thereof.

Mirror images of side and top/bottom views are within the scope of the claimed design even if not illustrated.

Features shown in broken lines do not form part of the claimed design.
